NATHAN JOSEPH LEIGH, OF NEW YORK, N. Y.

DISPLAY DEVICE

Application filed April 9, 1929. Serial No. 353,878.

My present invention relates generally to display devices, and has particular reference to the type of device which is primarily designed for use in store windows and the like.

5 It is a general object of my invention to provide a device which embodies, in combination, a means for receiving and accommodating actual articles of merchandise, and a means for displaying certain printed or illustrated subject matter relating thereto.

10 A more particular object is to provide such a device of a character which is exceptionally compact and simple in structural nature, whereby the articles of merchandise are efficiently and attractively positioned in close proximity to the displayed matter relating thereto, whereby the manufacture of the device is exceptionally inexpensive, and whereby the use thereof by the store owner is greatly facilitated and simplified.

15 One of the more specific objects of my invention is to provide a device which embodies certain elements or parts which are to be initially purchased and retained by the user, and which parts are capable of assembly with a variety of display cards or similarly prepared elements furnished to him from time to time by the manufacturer of the article to be displayed.

20 A further object is to provide a device which presents a uniquely attractive appearance to the eye of the observer whereby the efficient presentation of articles of merchandise is enhanced.

25 Briefly, my invention comprises the combination with a base and certain generically similar shelf elements, constructed in a particular manner, of two or more separably applicable column members adapted to carry the printed or illustrated subject matter. Preferably, the column members are of relatively inexpensive sheet material such as cardboard or the like.

30 One feature of my invention resides in constructing the column members in a peculiarly efficient manner whereby they may be inexpensively manufactured, collapsed during shipment or mailing thereof, and set up in association with the base and shelf elements

35 A particular feature of my invention resides in constructing my device in such a manner that a pair of the foregoing columns may be arranged in offset yet stable association. Thus, by positioning an upper column with its axis set somewhat to the rear of the axis of a lower column, a shelf element interposed between the two columns and suitably constructed will present an attractive and efficient area for the reception of articles of merchandise.

40 One of the important features of my invention resides in so constructing the columns referred to that the offset association thereof in the manner outlined above may be rendered practical and self-supporting without any recourse to extraneous supporting devices, braces, brackets, or the like.

45 A specific feature of my invention lies in constructing each column of a blank of sheet material which is bent longitudinally to provide a main tubular portion and a reinforcing portion extending outwardly therefrom. In a preferred construction, each column is shaped to provide a cross-section which conforms substantially to a figure 6, the loop of the 6 thereby providing the tubular portion referred to, and the stem of the 6 providing the reinforcement mentioned.

50 In general, it is an object of my invention to provide the several parts of my construction of a simple and standard nature, facilitating interchangeability and rendering possible a great flexibility of use. With respect to the column members, it is a specific object of my invention to design them in such a manner as to render them capable of manufacture upon wellknown machines and according to wellknown methods.

55 For the attainment of the foregoing objects and such other objects as may herein-after appear or be pointed out, I have illustrated several forms of my invention in the accompanying drawings, wherein—

60 Figure 1 is a general perspective view of a display device constructed in accordance with my present invention and fully assembled for use;

65 Figure 2 is a cross-sectional plan view

70 75 80 85 90 95 100

taken substantially along the line 2—2 of Figure 1;

Figure 3 is a side elevational view of the assembled device of Figure 1, a portion being broken away for the sake of clearness;

Figure 4 is an edge view of one of the column members in partially collapsed condition;

Figure 5 is a plan view of a somewhat modified blank from which a modified type of column member is to be constructed; and

Figure 6 is an exploded view showing the modified type of column in a position ready for assembly with a modified type of base.

15 In the form of device illustrated in Figures 1—3, I have shown the employment of a base 10, an intermediate shelf element 11, and a top shelf element 12; between the base 10 and the element 11 I have shown a column member 13, and between the elements 11 and 12, I have shown an upper column member 14. The column members 13 and 14 are preferably identical and are constructed as illustrated more fully in Figures 2 and 4.

25 The column member selected by me for description in the present case consists of a substantially rectangular blank of sheet material such as cardboard having the opposite substantially parallel lateral edges 15 and 16. 30 The blank is first scored along suitably spaced lines substantially parallel to the edges 15 and 16 whereby the same will ultimately be folded to provide the corners or edges 17, 18, 19, 20, and 21. The spacing of these scored lines is 35 of such a character that the edge 15 may be positioned in a lapped relationship illustrated most clearly in Figures 2 and 4 with respect to a midportion of the blank. This edge, i. e., the portion of the blank lying between the edges 15 and 20, is preferably adhesively secured to the midportion of the blank, thereby forming a substantially rectangular main tubular portion which is collapsible. It is to be noted that the lateral edge 16 is free and 40 extends tangentially outwardly from the main tubular portion, thereby forming a reinforcing portion whose purpose will be presently described. In the illustrated embodiment, a relatively large display element 45 in the form of a substantially flat cardboard blank 22 is adhesively secured to the outer face lying between the corners 17 and 18. This is the face which lies adjacent to that along which the edge 15 is adhesively secured in lapped relationship, and as a result, the reinforcing portion constituted of the free edge of the blank extends rearwardly from the card 22 when the column member is 50 opened up as shown in Figure 2.

60 I consider it a particular feature of my invention to construct the column member in the manner shown for the reason that the manufacture thereof may thereby be accomplished upon the wellknown folding and gluing machine instead of entirely by hand.

Upon reference to Figure 3, it will be noted that the base 10 is a substantially flat element adapted to rest in a substantially horizontal manner upon a suitable flooring or the like. On its upper surface and preferably toward the forward edge thereof, I provide a boss 23. Where this base is to be employed with a combination column member and display card of the character illustrated in Figure 4, the boss 23 is rectangular in cross-section and is so sized that the lower end of the tubular portion of the column member may fit snugly around the same.

70 The intermediate shelf element 11 is also a substantially flat and horizontally arranged element and is provided with the boss 24 on its lower surface and the boss 25 on its upper surface. The boss 24 is identical in cross-sectional configuration and size with the boss 23 and is adapted to fit snugly into the upper 75 end of the column member 13.

75 It is to be noted that the boss 24 is arranged toward one side of the shelf element 11 whereas the boss 25 is offset with respect thereto. In the form shown, the boss 25 is arranged toward the rear of the shelf element 11 whereby the assembly of the several component parts renders the forward portion of the shelf element 11 available for the reception 90 thereon of suitable articles of merchandise. 95

80 The top shelf element 12 is provided with a boss 26 on its lower surface, this boss being identical in cross-sectional configuration and size with the boss 25, whereby the lower and upper ends of the column member 14 may be 100 snugly fitted around the bosses 25 and 26 respectively.

85 All of the bosses 23—26 are preferably 105 identical in size and shape so that a set of standardized column members may be employed therewith. For example, in the illustrated form, the column members 13 and 14 may be interchanged, and it is contemplated that at periodic intervals either or both of these column members will be replaced by 110 others furnished to the user of the device.

90 To lend proper support to the structure, the reinforcing portion previously described is provided and it will be seen that this portion extends outwardly from the tubular portion of the lower column member toward the offset axis of the upper column member, thereby underlying and lending support to the shelf element 11 beneath the upper column member.

95 In the illustrated embodiment, I have shown only one intermediate shelf element, but it will be understood that my invention is not limited to this specific assembly, and that additional columns might be employed. For example, the top shelf element 12 might be replaced by a second intermediate shelf element which would be identical with the element numbered 11 and which would receive thereon a third column member identi- 100 105 110 115 120 125 130

cal with the members 13 and 14. In such an event, the top shelf element 12 would be placed at the upper end of this third column member and the total height of the entire device would thereby be increased. Such a higher device would be efficiently supported by virtue of the reinforcements on the two lowest columns, and with the employment of three columns, as thus suggested, the reinforcing portion of the present column 14, which is practically useless in the illustrated structure, would serve a valuable purpose the same as the reinforcing portion of the column 13 in the present case. It might also be desirable, with three or more columns, to increase the depth of the intermediate shelf element 11 so that there would be no overhanging of the reinforcing portions referred to.

The base 10 and the several shelf elements are preferably made of wood and it is contemplated that a set thereof will be purchased by the user of the device. From time to time, column members would be furnished to him and the foregoing description is sufficient to explain the simplicity with which such column members can be set up by the user. If desired, he may employ small tacks passing through the column members and entering the several bosses, but I have found that a proper design of the parts requires no such tacks and that the snug frictional engagement illustrated in the accompanying drawings is sufficient to render the entire structure stable.

In Figures 5 and 6 I have illustrated a modified form but I have omitted to show anything more than the base 27 and one column member, it being understood that a complete assembly of this modified construction would embody a suitably constructed intermediate shelf element or elements, at least two of the column members illustrated, and a suitably constructed top shelf element.

In Figure 5 I have illustrated the blank from which the column member of Figure 6 is to be constructed. It is partially scored and partially cut. It is substantially rectangular having the lateral side edges 28 and 29 and is scored along the lines 30 and 31 substantially parallel to these edges. It is also scored along the lines 32 and 33, but each of these last-mentioned scorings extends only part way across the blank, the cuts 34 and 35 being provided in the manner illustrated.

When this blank is suitably bent as shown in Figure 6, the edge 28 is secured to a midportion thereof in the same manner as before, but the scoring is of such a character that the main tubular portion thus constituted is substantially triangular. The free edge 29 again extends outwardly from the tubular portion to provide a reinforcing portion.

The cuts 34 and 35 enables me to dispense

entirely with an additional card of the character heretofore referred to at 22, because the front face of the column member defined by the scorings 32 and 33 is enlarged at the sides by the ears 36 and 37, each of which forms a portion of the blank which would otherwise have constituted part of the side faces of the tubular portion. I contemplate that suitable subject matter such as a trade mark or trade name, or a suitable illustration, may be contained on the front face of the column member and may extend outwardly on opposite sides onto the ears 36 and 37.

It is to be noted also that in this modified construction the base 27 is provided with a triangular boss 38, the reason for this being obvious, since the column member illustrated is to be snugly fitted thereover, in the same manner as hereinbefore described.

In general, it will be understood that the illustration herein contained merely explain the general nature of my invention. The tubular portions need not necessarily be rectangular or triangular, but may be circular, oval, elliptical, or similarly constructed in a variety of ways. Furthermore, other of the details herein described and illustrated may obviously be changed and altered by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. In a collapsible display device, a substantially flat and horizontally arranged base having a boss on its upper surface, a tubular collapsible column member removably applicable to said base and having its lower end snugly and frictionally engaging said boss, and a substantially flat and horizontally arranged shelf element having a boss on its under surface snugly and frictionally engaging within the upper end of said column member; said shelf element having a second boss on its upper surface for the reception thereover of a second similar tubular column member.

2. In a display device, a substantially flat and horizontally arranged base having a boss on its upper surface, a collapsible tubular column member removably applicable to said base and having its lower end snugly and frictionally engaging around said boss, and a substantially flat and horizontally arranged shelf element having a boss on its under surface snugly and frictionally engaging within the upper end of said column member; said shelf element having a second boss on its upper surface for the reception thereover of a second tubular column member, said second

boss being offset with respect to the boss on the undersurface of said shelf element.

3. In a collapsible display device, a base with an upwardly projecting boss, a tubular collapsible column member on said base with its lower end removably engaging frictionally around said boss, a shelf element on said column member and having a downwardly projecting boss removably engaging snugly and frictionally within the upper end of said column member, said shelf element having also an upwardly projecting boss, a second collapsible tubular column member on said shelf element with its lower end removably engaging frictionally around said last-mentioned boss, and a second shelf element on said second column member and having a substantially flat upper surface and a downwardly projecting boss removably engaging snugly and frictionally within the upper end of said second column member.

4. In a display device, a base with an upwardly projecting boss, a tubular column member on said base with its lower end removably engaging frictionally around said boss, a shelf element on said column member and having a downwardly projecting boss engaging frictionally within the upper end of said column member, said shelf element having also an upwardly projecting boss, a second tubular column member on said shelf element with its lower end removably engaging frictionally around said last-mentioned boss, and a second shelf element on said second column member and having a downwardly projecting boss frictionally engaging within the upper end of said second column member; the upwardly and downwardly projecting bosses on said first-named shelf element being slightly out of alignment, whereby said columns will be slightly offset with respect to each other.

5. In a display device, a pair of tubular column members superposed with their axes mutually offset, and a shelf element between said members and engaging the adjacent ends thereof, the lower column member having a reinforcing portion extending toward the axis of the upper column member so as to underlie and lend support to said shelf element beneath said upper column member.

6. In a display device, a pair of tubular column members superposed with their axes mutually offset, and a shelf element between said members and engaging the adjacent ends thereof, the lower column member having a reinforcing portion extending toward the axis of the upper column member so as to underlie and lend support to said shelf element beneath said upper column member; said lower column member comprising a blank of sheet material bent longitudinally to provide a cross-section which conforms substantially to a figure 6.

7. In a display device, a pair of tubular

column members superposed with their axes mutually offset, and a shelf element between said members and engaging the adjacent ends thereof, the lower column member having a reinforcing portion extending toward the axis of the upper column member so as to underlie and lend support to said shelf element beneath said upper column member; said lower column member comprising a blank of sheet material bent longitudinally to provide a cross-section which conforms substantially to a figure 6, the loop of said figure 6 being rectangular so that the column member is collapsible.

8. In a display device, a pair of tubular column members superposed with their axes mutually offset, and a shelf element between said members and comprising a substantially horizontal flat element, said shelf element having offset bosses on its lower and upper surfaces respectively for engagement within the upper and lower ends of the column members below and above said shelf element respectively.

9. In a display device, a pair of tubular column members superposed with their axes mutually offset, and a shelf element between said members and comprising a substantially horizontal flat element, said shelf element having offset bosses on its lower and upper surfaces respectively for engagement within the upper and lower ends of the column members below and above said shelf element respectively; the lower column member having a reinforcing portion which extends tangentially therefrom toward the axis of the upper column member so as to underlie and lend support to said shelf element beneath the boss on the upper surface of said shelf element.

10. As a new article of manufacture, a column member for a display device of the character described, comprising a blank of sheet material bent longitudinally to provide a cross-section conforming substantially to a figure 6, thereby providing a main tubular portion and a reinforcing portion extending tangentially therefrom.

11. As a new article of manufacture, a column member for a display device of the character described, comprising a blank of sheet material bent longitudinally to provide a cross-section conforming substantially to a figure 6 whose loop is rectangular, thereby providing a collapsible main tubular portion and a reinforcing portion extending tangentially therefrom.

12. As a new article of manufacture, a column member for a display device of the character described, comprising a blank of sheet material bent longitudinally to provide a main portion of tubular cross-section and a reinforcing portion extending outwardly from said main portion.

13. As a new article of manufacture, a col-

umn member for a display device of the character described, comprising a blank of sheet material bent longitudinally to provide a main portion of tubular cross-section and 5 a reinforcing portion extending outwardly from said main portion, one lateral edge of the blank being adhesively secured in lapped position to a midportion of the blank, whereby said reinforcing portion will be constituted of the free edge portion of the blank. 10

14. As a new article of manufacture, a column member for a display device of the character described, comprising a blank of sheet material bent longitudinally to position 15 one lateral edge in lapped relationship to a midportion of the blank, thereby defining a main tubular portion, the opposite lateral edge being free and extending outwardly from said main portion to provide a 20 reinforcement.

15. As a new article of manufacture, a combination column member and display card for a display device of the character described, comprising a blank of sheet material 25 bent longitudinally to position one lateral edge in lapped relationship to a midportion of the blank, the blank being bent so that the tubular portion thus formed will be rectangular in cross-section, said edge being adhesively secured to said midportion 30 and the opposite lateral edge being free and extending tangentially from said tubular portion to provide a reinforcement, and a relatively large display element overlying 35 and secured to the rectangular tubular portion on the face adjacent to that on which said adhesively lapped relationship exists.

In witness whereof I have signed this specification this 30th day of March, 1929.
